UNITED STATES PATENT OFFICE.

CHARLES F. PFLANZE, OF ST. LOUIS, MISSOURI.

CUTTING-MACHINE.

1,302,211.

Specification of Letters Patent. Patented Apr. 29, 1919.

Application filed July 2, 1917. Serial No. 178,095.

To all whom it may concern:

Be it known that I, CHARLES F. PFLANZE, citizen of the United States of America, a resident of the city of St. Louis, State of Missouri, have invented certain new and useful Improvements in Cutting-Machines, of which the following is a full, clear, and exact description, reference being had to the accompanying drawings, forming a part of 10 this specification.

My invention relates to improvements in cutting machines, and more particularly to a gage adapted for use in performing a number of different cutting operations. The 15 main object of the invention is to cut the material very accurately and at the same time effect a saving of time and labor in adjusting the material relative to the cutting edge of the knife. The new structure is 20 well adapted for use in making envelop blanks. It can be used in making many different symmetrical angular cuts, and also for the purpose of truing and trimming non-symmetrical envelop blanks formed by 25 an envelop die.

With the foregoing and other objects in view the invention comprises the novel construction, combination and arrangement of parts hereinafter more specifically described 30 and illustrated in the accompanying drawings wherein is shown the preferred embodiment of the invention; however, it is to be understood that the invention comprehends changes, variations and modifications which 35 come within the scope of the claims hereunto appended.

Figure I is a plan view showing a portion 40 of a cutting machine provided with a main gage and an auxiliary gage.

Fig. II is a longitudinal section taken approximately through the center of the auxiliary gage.

Fig. III is an enlarged vertical section taken approximately on the line III—III, 45 Fig. II.

Fig. IV is a plan view of one of the stop arms.

Fig. V is a side elevation of the stop arm shown in Fig. IV.

Fig. VI is a vertical section showing the cutting elements and the gages.

Fig. VII is a fragmentary plan view showing the main gage, the auxiliary gage, and the work fitted to the auxiliary gage, 55 the cutting line being shown by dotted lines.

Fig. VIII is a view similar to Fig. VII,

showing the auxiliary gage in a different position.

Fig. IX is a fragmentary plan view of a portion of the auxiliary gage showing gage 60 members slightly different from the similar members shown in Fig. VIII.

Fig. X is a fragmentary plan view showing the manner in which the auxiliary gage is used in truing and trimming envelop 65 blanks. To illustrate the invention I have shown a paper cutting machine provided with a horizontal work table A, a knife carrier B (Fig. VI) movable toward and away from said table, a blade 1 secured to said 70 knife carrier, and a clamping bar C movable toward and away from the table. Any suitable mechanism may be used to reciprocate the knife carrier B and clamp bar C. D designates a main gage, arranged parallel 75 with the blade 1 and adapted to be engaged by the work in performing some of the cutting operations. The main gage D rests upon the horizontal table A and it is provided with a depending lug 2 which extends 80 through a slot 3 in said table. An adjusting screw 4 (Fig. VI) fitted to the lug 2 may be adjusted to move the main gage D toward and away from the cutting line.

The auxiliary gage preferably comprises 85 a pair of gage members 5 arranged at an angle to each other to form an angular recess for the work. These gage members 5 may be pivotally connected together at 6, as shown in Fig. I, or they may be made as 90 shown at 5' in Figs. VII, VIII and IX. The gage members 5 or 5' rest upon the table A and they have flat vertical faces adapted to be engaged by the work W, which may consist of superposed sheets of 95 paper, as shown in Figs. VI, VII and VIII. Each gage member 5 or 5' is provided at its upper edge with a lug 7 having a circular opening for the reception of a vertical gage post 8. The gage posts are shown most 100 clearly in Figs. I, II and VI. The gage members 5 or 5' may be readily lifted from the gage posts 8, without disturbing any of the other elements of the auxiliary gage.

The gage holder comprises a pair of arms 105 9 to which the gage posts 8 are secured, a pivot pin 10 passing through said arms and secured to an abutment block E, and a screw 11 for adjusting the arms 9 toward and away from each other. This adjusting 110 screw is fitted to threaded posts 12, the latter being pivoted to the arms 9. Right and left

hand threads are formed on the screw member 11, as shown in Fig. I, so that the arms 9 will move toward or away from each other in response to rotary movements of this 5 double screw.

It will now be understood that the gage holding arms 9 may be adjusted to receive different gage members 5 or 5', also to move the pivoted gage members 5 toward and 10 away from each other. In making an adjustment of this kind, the gage holding arms move in opposite directions about the axis of their pivot 10. These arms can also be moved simultaneously, in the same direction, 15 about the axis of pivot 10 for the purpose of shifting the auxiliary gage from the position shown in Fig. VII to the position shown in Fig. VIII.

To accomplish this in a highly desirable 20 manner, the gage holding arms are secured to an oscillatory carriage F consisting of a horizontal plate and a pair of links 13 and 14 pivoted to said plate. The pivot pin 10 passes through the oscillatory carriage F, 25 and said carriage can be turned about the axis of said pin. The gage holding arms 9 can be adjusted independently of the oscillatory carriage in the manner previously pointed out, and the carriage may be turned 30 for the purpose of moving the arms 9, simultaneously, in the same direction.

To obtain this simultaneous movement the screw 11, secured to the arms 9, passes through the link 13 which forms part of the 35 oscillatory carriage, and collars 15 engaging opposite sides of link 13, are secured to the screw 11. The link 13 is preferably slotted (Fig. II) to receive the screw 11.

In forming angular cuts symmetrical with 40 the cutting line, it is necessary to locate the work W in two predetermined positions relative to said line, as shown by Figs. VII and VIII. This is accomplished by predetermining one of the positions and then adjusting 45 a stop device so that the auxiliary gage may be easily and quickly shifted from one position to another.

The stop device comprises a pair of stop 50 arms 17, loosely mounted on the pivot 10, an adjusting screw 11' connecting said stop arms, and collars 15' fixed to said screw. Collars 15' lie at opposite sides of the link 55 14 which forms part of the oscillatory carriage F. Therefore, the stop arms 17 move with the oscillatory carriage. The screw 11' may be adjusted independently of the carriage for the purpose of moving the stop arms 17 toward and away from each other. A stationary stop lug 18, fixed to the abutment 60 device E, co-operates with the stop arms 17 to limit the movements of the oscillatory carriage F, thereby limiting the movement of the gage members 5 or 5'. When the stop arms 17 are adjusted as shown in Fig. I, 65 they engage the stationary stop lug 18, there-

by preventing the oscillatory carriage F from turning on the axis of pivot 10. This is due to the fact that the link 14 forming part of the oscillatory carriage, is confined between the collars 15' on the screw 11', 70 while the stop arms 17, also secured to said screw, engage the stationary lug 18.

When the stop arms 17 are adjusted away from each other, as shown in Figs. VII and VIII, the auxiliary gage device may be readily 75 shifted from one position to another, and it will be stopped in the desired positions by the arms 17 and the stationary lug 18. Symmetrical cuts, at various different angles, can be made very accurately by adjusting 80 the stop device, and when the structure is once adjusted, cuts of the same kind can be made repeatedly without further adjustment.

A well-known type of paper cutting machine 85 includes a main gage D, parallel with the cutting edge of the blade 1, and a work table A provided with the slot 3. To facilitate the application of my auxiliary gage to a machine of this kind, the abutment device 90 E is provided with a flat abutment flange 20 which engages the main gage D, and also provided on its bottom face with a lug 21 closely fitted to the walls of the slot 3. All of the movable elements of the auxiliary 95 gage are secured to the abutment device E, and the latter can be very easily fitted to the work table A and main gage D, so as to very accurately locate the auxiliary gage in the desired position with respect to the cutting 100 edge.

When all of the preliminary adjustments are made for using the gage, the various members should be mounted so that the oscillating carriage F moves freely about the 105 pivot 10, and at the same time the members 9 and 17 should be held together by the pivot 10, so they act as one piece and do not freely move relative to each other, but are secured to the oscillating carriage so as to move 110 around the pivot 10 with said carriage.

Envelop blanks are sometimes formed by the use of a die conforming to the configuration of the blanks, the die being forced downwardly onto a pile of paper so as to form a 115 large number of blanks at one operation. The blanks formed in this manner are usually more or less unsymmetrical, this being due to the fact that the sheets of paper slip on each other and become disarranged 120 during the cutting operation. When folded, the blank constitutes a rectangular figure, and all of the flaps should be symmetrical with the edges of this figure. The rectangular figure in question is indicated by the dotted lines H in Fig. X. If the various flaps 125 are not symmetrical with this figure, the envelop will be more or less unsymmetrical. I, therefore, use my auxiliary gage in trimming the edges of blanks formed by dies, and 130

when so trimmed, all of the flaps are symmetrical with the rectangular figure H shown in Fig. X. To accomplish this, the gage members 5 or 5' are lifted from the gage posts 8, and these oppositely disposed gage posts are then adjusted to enter the recesses 25 at the corners of the rectangular figure. The pile of blanks are thrust against the vertical faces of the gage posts 8, and the 10 corners of the rectangular figures are thus placed in vertical alinement with each other. The gage holding arms 9 and their gage posts 8 can be adjusted from one position to another as already pointed out in referring to Figs. VII and VIII, and by following this practice, all of the flaps or wings can be trimmed and made symmetrical with the rectangular figure H.

I claim:—

- 20 1. In a cutting machine, a work table, a blade for cutting the work on said table, a gage for predetermining the location of the work relative to said blade, said gage comprising diverging gage members arranged 25 to form an angular recess for the work, a gage holder to which diverging gage members are secured, an oscillatory carriage to which said gage holder is pivoted, said gage holder being movable about the axis of its 30 pivot to locate said diverging gage members in different positions relative to the work, and adjustable means whereby said oscillatory carriage is stopped in its two extreme positions.
- 35 2. In a cutting machine, a work table, a blade for cutting the work on said table, a gage for predetermining the location of the work relative to said blade, said gage comprising diverging gage members arranged 40 to form an angular recess for the work, a pivotally mounted gage holder including adjustable gage holding members to which said diverging gage members are secured, said gage holder being movable about the 45 axis of its pivot to locate said diverging gage members in different positions relative to the work, and means for stopping said gage holder in two different extreme positions, the stopping means being adjustable 50 independently of said gage holding members to vary the extreme positions of the gage holder.
- 55 3. In a cutting machine, a work table, a blade for cutting the work on said table, a gage for predetermining the location of the work relative to said blade, said gage comprising diverging gage members arranged to 60 form an angular recess for the work, and a gage holder including two pivotally mounted arms to which said diverging gage members are secured, said pivotally mounted arms being adjustable toward and away from each other about the axis of their pivot, and said arms being movable simultaneously in the same direction about said 65

axis to locate said diverging gage members in different positions relative to the blade.

4. In a cutting machine, a work table, a blade for cutting the work on said table, a gage for predetermining the location of the 70 work relative to said blade, said gage comprising oppositely disposed gage members adapted to be engaged by the work, and a holder for said gage members, said holder comprising gage holding members adjustable 75 relative to the gage and said holder being adjustable to different predetermined positions to locate said oppositely disposed gage members in different positions symmetrical with respect to said blade.

80 5. In a cutting machine, a work table, a blade for cutting the work on said table, a gage for predetermining the location of the work relative to said blade, said gage comprising oppositely disposed gage members 85 adapted to be engaged by the work, a holder for said gage members, said holder being adjustable to different predetermined positions to locate said oppositely disposed gage members in different positions symmetrical with 90 respect to said blade, and an adjustable stop device comprising adjustable stop members whereby said holder is stopped in said predetermined positions.

95 6. In a cutting machine, a work table, a blade for cutting the work on said table, a gage for predetermining the location of the work relative to said blade, said gage comprising oppositely disposed gage members 100 adapted to be engaged by the work, and a holder for said gage members including oppositely disposed pivotally mounted gage holding members movable toward and away from each other, said pivotally mounted gage holding members being also movable simultaneously in the same direction to locate the gage members in different positions 105 symmetrical with respect to said blade.

110 7. In a cutting machine, a work table, a blade for cutting the work on said table, a gage for predetermining the location of the work relative to said blade, said gage comprising oppositely disposed gage members 115 adapted to be engaged by the work, a holder for said gage members including oppositely disposed pivotally mounted gage holding members movable toward and away from each other, said pivotally mounted gage holding members being also movable simultaneously in the same direction to locate the 120 gage members in different positions symmetrical with respect to said blade, and a stop device for limiting the movements of said pivotally mounted gage holding members to predetermine the positions of the 125 gage members.

125 8. In a cutting machine, a work table, a blade for cutting the work on said table, a gage for predetermining the location of the work relative to said blade, said gage com- 130

prising oppositely disposed gage members adapted to be engaged by the work, a pair of gage holding arms to which said gage members are secured, and an oscillatory carriage to which said gage holding arms are pivoted, each of said gage holding arms being movable about the axis of its pivot independently of said oscillatory carriage, and said gage holding arms being movable with said oscillatory carriage to locate the gage members in different positions symmetrical with respect to said blade.

9. In a cutting machine, a work table, a blade for cutting the work on said table, a gage for predetermining the location of the work relative to said blade, said gage comprising oppositely disposed gage members adapted to be engaged by the work, a pair of gage holding arms to which said gage members are secured, an oscillatory carriage to which said gage holding arms are pivoted, each of said gage holding arms being movable about the axis of its pivot independently of said oscillatory carriage, and said gage holding arms being movable with said oscillatory carriage to locate the gage members in different positions symmetrical with respect to said blade, and a stop device associated with said carriage to predetermine the symmetrical positions of said gage members.

10. In a cutting machine, a work table, a blade for cutting the work on said table, a gage for predetermining the location of the work relative to said blade, said gage comprising oppositely disposed gage members adapted to be engaged by the work, a holder for said gage members, and a carriage for said holder, said holder being movable with said carriage to locate said oppositely disposed gage members in different positions symmetrical with said blade, and said holder being adjustable independently of said carriage.

11. In a cutting machine, a work table, a blade for cutting the work on said table, a gage for predetermining the location of the work relative to said blade, said gage comprising oppositely disposed gage members adapted to be engaged by the work, a holder for said gage members, a carriage for said holder, said holder being movable with said carriage to locate said oppositely disposed gage members in different positions symmetrical with said blade, and a stop device whereby the carriage is stopped in two different positions to predetermine the symmetrical positions of said gage members, said stop device comprising stop members movable to different positions to change the symmetrical positions of said gage members.

12. In a cutting machine, a work table, a blade for cutting the work on said table, a gage for predetermining the location of the work relative to said blade, said gage comprising oppositely disposed gage members

adapted to be engaged by the work, a holder for said gage members, a carriage for said holder, said holder being movable with said carriage to locate said oppositely disposed gage members in different positions symmetrical with said blade, and a stop device whereby the carriage is stopped in two different positions to predetermine the symmetrical positions of said gage members, said stop device comprising a pair of stop members carried by said carriage, and said stop members being adjustable independently of the carriage.

13. In a cutting machine, a work table, a blade for cutting the work on said table, a gage for predetermining the location of the work relative to said blade, said gage comprising oppositely disposed gage members adapted to be engaged by the work, a holder for said gage members including a pair of oppositely disposed gage holding members, an oscillatory carriage to which said gage holding members are pivoted, an adjusting screw rotatably fitted to said oscillatory carriage and fitted to said gage holding members, said adjusting screw being free to move independently of said oscillatory carriage so as to adjust said gage holding members toward and away from each other, and said adjusting screw and gage holding members being movable with said oscillatory carriage to locate said gage members in different positions symmetrical with said blade.

14. In a cutting machine, a work table, a blade for cutting the work on said table, a gage for predetermining the location of the work relative to said blade, said gage comprising oppositely disposed gage members adapted to be engaged by the work, a holder for said gage members including a pair of oppositely disposed gage holding members, an oscillatory carriage to which said gage holding members are pivoted, an adjusting screw rotatably fitted to said oscillatory carriage and fitted to said gage holding members, said adjusting screw being free to move independently of said oscillatory carriage so as to adjust said gage holding members toward and away from each other, and said adjusting screw and gage holding members being movable with said oscillatory carriage to locate said gage members in different positions symmetrical with said blade, stop arms pivoted to said oscillatory carriage, a screw for adjusting said stop arms toward and away from each other, the last mentioned screw being carried by said oscillatory carriage, and a stationary stop member arranged between said stop arms to limit the movements of said oscillatory carriage.

15. In a cutting machine, a work table, a blade for cutting the work on said table, a main gage mounted on said table and adapted to be engaged by the work acted upon by said blade, said main gage being

- parallel with said blade, and an auxiliary gage associated with said blade and main gage to cut the work at different angles symmetrical with said blade, said auxiliary gage including oppositely disposed gage members adapted to be engaged by the work, and a holder for said oppositely disposed gage members, said holder being adjustable to different predetermined positions to locate said oppositely disposed gage members in different positions symmetrical with said blade, and an adjustable stop device whereby said holder is stopped in said different symmetrical positions.
- 5 16. In a cutting machine, a work table provided with a slot, a blade for cutting the work on said table, a main gage mounted on said table and adapted to be engaged by the work, said main gage being adjustable toward and away from said blade, and an auxiliary gage associated with said blade and main gage to cut the work at different angles symmetrical with said blade, said auxiliary gage comprising oppositely disposed gage members adapted to be engaged by the work, a holder for said oppositely disposed gage members, and an abutment device to which said holder is adjustably secured, said abutment device being engaged 50 with said main gage and provided with an extension which lies in said slot in the work table.
17. In a machine for trimming sheets of paper having recessed edges, a work table, a blade for cutting piles of said paper sheets on said work table, and a gage for predetermineding the location of the paper sheets relative to said blade, said gage comprising
- 55 oppositely disposed gage members arranged to lie in the recessed portions of said paper sheets, so as to locate the recesses in each sheet in alinement with the corresponding recesses in the other sheets.
18. In a machine for trimming piles of envelop blanks having recesses forming the corners of a rectangular figure, a work table, a blade for trimming the blanks on said table, and a gage for alining the recesses of each blank with the corresponding recesses in the other blanks and at the same time predetermineding the location of the rectangular figures relative to said blade, said gage comprising oppositely disposed gage members arranged to enter the recesses at opposite edges of the blanks.
19. In a machine for trimming piles of envelop blanks having recesses forming the corners of a rectangular figure, a work table, a blade for trimming the blanks on said table, and a gage for alining the recesses of each blank with the corresponding recesses in the other blanks and at the same time predetermineding the location of the rectangular figures relative to said blade, said gage comprising oppositely disposed gage members having vertical faces adapted to enter the recesses at opposite edges of the blanks, and a holder for said gage members, said holder being adjustable to different positions so as to locate said oppositely disposed gage members in different positions symmetrical with said blade.
- 55 60 65 70

In testimony that I claim the foregoing I hereunto affix my signature.

CHARLES F. PFLANZE.
